GOLF CLUB OR SIMILAR ARTICLE

William R. Pomper, 207 Woodland,
Highland Park, Ill. 60035

Filed Oct. 26, 1973, Ser. No. 409,799

Term of patent 14 years

Int. Cl. D21—02

U.S. Cl. D34—5 GC

FIG. 1 is a front elevational view of a golf club or similar article showing my new design, the opposite side being a mirror image thereof;

FIG. 2 is an elevational view taken from the right side of FIG. 1;

FIG. 3 is an elevational view taken from the left side or FIG. 1;

FIG. 4 is a top plan view;

FIG. 5 is a bottom plan view;

FIG. 6 is a side elevational view with the telescoping handle in collapsed position; and

FIG. 7 shows a side elevational view of another embodiment of the head portion, the opposite side thereof being a mirror image.

I claim:

The ornamental design for a golf club or similar article, substantially as shown and described.
